UNITED STATES PATENT OFFICE.

SARAH S. HOWARTH, OF NEW YORK, N. Y.

BICYCLE ATTACHMENT.

SPECIFICATION forming part of Letters Patent No. 627,693, dated June 27, 1899.

Application filed January 30, 1899. Serial No. 703,794. (No model.)

To all whom it may concern:

Be it known that I, SARAH S. HOWARTH, a subject of the Queen of Great Britain, and a resident of New York, (Brooklyn,) county of 5 Kings, and State of New York, have invented certain new and useful Improvements in Bicycle Attachments, of which the following is a specification, reference being had to the accompanying drawings, forming a part there- 10 of, in which similar letters and numerals of reference indicate corresponding parts.

This invention relates to improvements in bicycle attachments.

Bicycle-riders are frequently attacked and 15 injured by vicious dogs while traveling over country roads; and this invention has for its object to supply an efficient and easily-operated means for repelling dogs of this class.

The device is simple in construction, light 20 in weight, and inexpensive, and it is adapted for attachment to any common form of bicycle-frame.

The invention will be hereinafter fully described, and specifically set forth in the annexed claim.

In the accompanying drawings, forming part of this specification, Figure 1 is a side elevation of a portion of a bicycle having my improved appliance attached thereto. Fig. 30 2 is a perspective view of the appliance detached, and Fig. 3 is a detail sectional elevation of a portion of the device.

In the practice of my invention I employ a plurality of boxes A, adapted to contain snuff, 35 pepper, or other pulverized material of a class calculated to repel the advances of a dog. These said boxes are secured to suitable parts of the bicycle-frame by means of clamps B, of any adapted construction, which are connected thereto. Each of these said boxes is provided with a removable lid a and an air-inlet tube a', and these said inlet-tubes communicate with flexible tubing C, which leads to an ordinary compressible bulb D for the 40 purpose of supplying air-pressure to the boxes. Each box is supplied with a series of perforations a² for outlet of pepper or other powder

contained therein. These perforations may be placed through the side of the box, as illustrated at 1, Fig. 1 of the drawings, or 50 through the rear wall thereof, as illustrated at 2, Fig. 1 of the drawings, the location of the perforations depending upon the position of the boxes on the frame of the bicycle.

In practice I will preferably use but two 55 boxes, located upon each front fork of the wheel; but it is obvious that any suitable number of boxes may be employed, and in all cases the flexible tubes C leading therefrom communicate with a common tube C', which 60 is led from the compressible bulb D. The bulb D is fastened to the handle-bar by means of a strap d; but I do not confine myself to any specific means for fastening nor to any particular location upon the bicycle-frame, 65 as the flexible air-supplying tubes may readily be led to any part of the machine.

In the operation and use of the device when a dog attacks a rider it is simply necessary to compress the bulb, which forces the pepper 70 contained within the boxes out through the perforated portions thereof by means of air-pressure, and it is obvious that a sprinkling of red pepper or other similar substance will immediately cause a dog to desist from further attack.

Having thus described my invention, what I claim as new, and desire to secure by Letters Patent, is—

As a bicycle attachment for repelling the 80 attacks of dogs, the combination of a perforated box containing pepper or other substance, and a flexible tube and a compressible bulb, and means for attaching the device to the frame of a bicycle, substantially as 85 shown and described.

In testimony that I claim the foregoing as my invention I have signed my name, in presence of two witnesses, this 26th day of January, 1899.

SARAH S. HOWARTH.
